CLAIM

The ornamental design for a LED lamp, as shown and described.

DESCRIPTION

FIG. 1 is a front view of an LED lamp, showing our design;
FIG. 2 is a rear view thereof;
FIG. 3 is a left side view thereof;
FIG. 4 is a right side view thereof;
FIG. 5 is a top view thereof;
FIG. 6 is a bottom view thereof;
FIG. 7 is a top perspective view thereof;
FIG. 8 is a bottom perspective view thereof; and,

(Continued)

FIG. 9 is a top perspective view thereof showing a cover in an open position and additional environment. The broken line showing in the Figures illustrates portions of the LED lamp or of the environment and forms no part of the claimed design.

1 Claim, 9 Drawing Sheets
